SUCTION CLEANER

Leslie M. Jones, North Canton, Ohio, assignor to
 The Hoover Company, North Canton, Ohio, a
 corporation of Ohio

Application July 12, 1939, Serial No. 283,935

2 Claims. (Cl. 15—182)

The present invention relates to suction cleaners in general and particularly to new and novel improvements in rotary agitators for suction cleaners. More specifically the invention comprises a suction cleaner agitator which includes a flexible agitating element having a supporting base formed of deformable material.

It is an object of the present invention to provide a new and improved suction cleaner. It is another object of the invention to provide a new and improved agitator for a suction cleaner. Another object of the invention is to provide a new and improved agitating element for a suction cleaner agitator. A further object of the invention is to provide an adjustable agitating element for a suction cleaner agitator which is deformable to permit of adaptation to the retaining means of the agitator. Still another object of the invention is to provide a removable brush element for a suction cleaner agitator which embodies flexible bristles and a deformable rubber back. These and other more specific objects will appear upon reading the following specification and claims and upon considering in connection therewith the attached drawings to which they relate.

Referring now to the drawings in which a preferred embodiment of the invention is illustrated, and in which the same reference character refers to the same part throughout:

Figure 1 illustrates a side elevation of a suction cleaner embodying the present invention with certain parts of the cleaner broken away and shown in section;

Figure 2 is a side elevation of a rotary agitator embodying the invention;

Figure 3 is a section through the agitator upon the line 3—3 of Figure 2 and illustrates the removable brush element positioned in its new brush or inner radial position;

Figure 4 is a view similar to Figure 3 but with the element positioned in its worn brush or outer radial position;

Figure 5 is a longitudinal section through the agitator taken along the brush seat;

Figure 6 is a view in perspective of the brush element and seat removed from the agitator body;

Figure 7 is a view in perspective of the removable agitating element itself and illustrates the deformation which takes place in that element when positioned in the agitator by the dotted line showing.

The modern agitator for a suction cleaner embodies rigid beating elements and flexible brushing elements, the latter being subject to wear in use. When such wear occurs the flexible element

decreases in length and an adjustment is required to increase its radial extension. For maximum effectiveness the radial projection of the flexible brushing element must be substantially that of the rigid beating element. Rotary agitators have been made in which no provision was made for such adjustment. There have been agitators in which the brush element is manually adjustable and the most satisfactory of these have been those in which the element is removable and repositioned in a second adjustment at a greater radial extension. The present invention is an improvement in the latter type. With the incorporation of helically extending brush elements the adjustment of the element becomes a more difficult problem and the present invention has solved that problem in a simple and easy manner.

Referring again to the drawings and to Figure 1 in particular, a modern suction cleaner is illustrated which is seen to comprise a nozzle 1 which is interiorly connected through an air passage way 2 to a fan chamber 3 which houses a suction-creating fan 4 carried by the depending end of the motor shaft 5. The latter is formed as a driving pulley 6 at its lower end and, through the interpositioning of a power-transmitting belt 7 rotates an agitator, indicated generally by the reference character 8, positioned within the nozzle 1. Fan chamber 3 is provided with an exhaust outlet 9 which is formed with bag-attaching means 10 which are manually operable and which are illustrated as securing in place a dirt-filtering bag 11. Above the fan chamber 3 is positioned a motor casing 12 which houses an unshown driving motor the shaft 5 of which is seen to extend downwardly through the fan chamber 3. The entire cleaner body is movably supported upon wheels 13 and, in the usual manner, a pivoted handle 14 is provided by which the operator can exert the necessary propelling and guiding forces. In its general outline the cleaner is well known in the art.

Referring now to Figures 2 to 7, inclusive, the rotary agitator and the removable brush element comprising the present invention are illustrated in detail. The agitator 8 is seen to comprise a cylindrical, hollow body 15, the ends of which are closed by an end plate 16 which is centrally counterbored to seat a ball bearing 17 which is rotatably supported by the shaft 18 extending completely through the agitator and from the ends thereof. A thread guard 19 is carried at each end of the shaft 18 adjacent the bearing and end plates 17 and 16, respectively, and provides means which effectively prevents the accumula-

tion of foreign material at the bearing. The body 15 is formed substantially at its center with a reduced grooved portion which forms a pulley 22 and the agitator is seen to be substantially identical upon the opposite sides thereof.

The body 15 is formed with inwardly sloping helically extending shoulders 24 to which the helically extending brush seat 25 is removably secured by screws 26. Brush seat 25, as is the most clearly illustrated in Figure 6, is adapted to be removed entirely from the agitator body and is formed with an end closure 27 at one end while its opposite end remains open. Its central portion in any section is substantially rectangular and inwardly extending shoulders 29 are formed upon the opposite sides thereof and extend the length of the seat.

Within the brush seat 25 is positioned a brush element 30 which is seen to comprise an extended row of flexible brush bristles which are mounted and secured within a back 31 of substantially the size of the interior dimensions of the brush seat 25. The back 31 is formed along each of its sides with two parallel grooves 32 at different heights thereon. As is clearly illustrated in Figures 3 and 4 these grooves are adapted to enclose the inwardly extended shoulders 29 formed in the brush seat and the brush is adapted to be positioned in an inner radial or lower position, as illustrated in Figure 3, when the shoulders seat within the upper pair of grooves. The brush is also adapted to be positioned in an outer radial or upper position when the shoulders seat within the lower pair of grooves, as illustrated in Figure 4. The brush element 30 is characterized in that the back 31 thereof is formed of a pliant, flexible and deformable material such as a rubber of medium hardness. The brush element, including its back, is made straight, the back being either molded or extruded. Because it is normally straight, the back is more easily and economically made and because it is flexible and

deformable it can conform to the shape of the helically extending brush seat as well as an element which is initially made into a helical shape. Initial cost of manufacture is reduced and likewise handling costs and packing costs are minimized because of the shape.

The agitator constructed in accordance with the invention is completed by the provision upon the exterior surface thereof, in the common and well known manner, of a rigid, helically extending beater element 35 which cooperates with the flexible brush 30 in the agitation of the surface covering undergoing cleaning.

I claim:

1. In a rotary agitator for a suction cleaner, a cylindrical body, a unitary helically extending brush seat removably retained on said body and formed with an open end, shoulders in said seat upon the opposite sides thereof, a brush including a back formed with a plurality of shoulder-receiving grooves upon the opposite sides thereof and at different heights thereon positioned in said seat, said back being of rubber, normally straight, and deformed helically by said seat, said brush being displaceable from the end of said seat.

2. In a rotary agitator for a suction cleaner, a cylindrical body, an helically extending brush seat positioned in said body and formed with inwardly extending abutment elements upon the opposite sides thereof, and a brush including a back formed with a plurality of spaced shoulder-receiving grooves upon the opposite sides thereof and at different heights thereon adapted to be selectively positioned in various radial positions in said seat with said abutments positioned in pairs of said grooves, said back being made of a deformable material such as rubber which is normally straight but sufficiently resilient to be deformed to conform to the curvature of said seat in the various adjusted positions.

LESLIE M. JONES.
